(57) **CLAIM**

The ornamental design for an article of furniture, as shown and described.

DESCRIPTION

FIG. 1 is a front perspective view of an article of furniture showing our new design;
FIG. 2 is a top view thereof;
FIG. 3 is a left side view thereof;
FIG. 4 is a front view thereof;
FIG. 5 is a right side view thereof;
FIG. 6 is a rear view thereof;
FIG. 7 is a front perspective view of an alternative embodiment of an article of furniture showing our new design;
FIG. 8 is a top view thereof;
FIG. 9 is a left side view thereof;
FIG. 10 is a front view thereof;
FIG. 11 is a right side view thereof;
FIG. 12 is a rear view thereof;
FIG. 13 is a front perspective view of an alternative embodiment of an article of furniture showing our new design;
FIG. 14 is a top view thereof;
FIG. 15 is a left side view thereof;
FIG. 16 is a front view thereof;
FIG. 17 is a right side view thereof;
FIG. 18 is a rear view thereof;
FIG. 19 is a front perspective view of an alternative embodiment of an article of furniture showing our new design;
FIG. 20 is a top view thereof;
FIG. 21 is a left side view thereof;
FIG. 22 is a front view thereof;
FIG. 23 is a right side view thereof;
FIG. 24 is a rear view thereof;
FIG. 25 is a front perspective view of an alternative embodiment of an article of furniture showing our new design;
FIG. 26 is a top view thereof;
FIG. 27 is a left side view thereof;
FIG. 28 is a front view thereof;
FIG. 29 is a right side view thereof;
FIG. 30 is a rear view thereof;
FIG. 31 is a front perspective view of an alternative embodiment of an article of furniture showing our new design;
FIG. 32 is a top view thereof;
FIG. 33 is a left side view thereof;
FIG. 34 is a front view thereof;
FIG. 35 is a right side view thereof;
(Continued)

FIG. 36 is a rear view thereof;
 FIG. 37 is a front perspective view of an alternative embodiment of an article of furniture showing our new design;
 FIG. 38 is a top view thereof;
 FIG. 39 is a left side view thereof;
 FIG. 40 is a front view thereof;
 FIG. 41 is a right side view thereof;
 FIG. 42 is a rear view thereof;
 FIG. 43 is a front perspective view of an alternative embodiment of an article of furniture showing our new design;
 FIG. 44 is a top view thereof;
 FIG. 45 is a left side view thereof;
 FIG. 46 is a front view thereof;
 FIG. 47 is a right side view thereof;
 FIG. 48 is a rear view thereof;
 FIG. 49 is a front perspective view of an alternative embodiment of an article of furniture showing our new design;
 FIG. 50 is a top view thereof;
 FIG. 51 is a left side view thereof;
 FIG. 52 is a front view thereof;
 FIG. 53 is a right side view thereof; and,
 FIG. 54 is a rear view thereof.
